(57) **CLAIM**

We claim the ornamental design for cap for containers of air-fresheners, insecticides, and the like, as shown.

DESCRIPTION

FIG. 1 is a top, front perspective view of a cap for containers of air-fresheners, insecticides, and the like showing the new design.

FIG. 2 is a bottom perspective view thereof.

FIG. 3 is a front elevational view thereof.

FIG. 4 is a top plan view thereof; and,

FIG. 5 is a rear elevational view thereof.
